UNITED STATES PATENT OFFICE.

MORTIMER J. SILBERBERG, OF CHICAGO, ILLINOIS.

TIE-PLATE.

1,151,728.

Specification of Letters Patent. Patented Aug. 31, 1915.

Application filed June 5, 1914. Serial No. 843,289.

To all whom it may concern:

Be it known that I, MORTIMER J. SILBERBERG, a citizen of the United States, residing at Chicago, in the county of Cook and State 5 of Illinois, have invented certain new and useful Improvements in Tie-Plates, of which the following is a specification.

My invention relates to railway track construction and has particular reference to a 10 novel tie plate and clip particularly adapted for use with screw spikes.

It is common practice on many railroads to place beneath the rails on each tie a tie plate in order to increase the bearing surface 15 between the rail and the plate. Such plates have taken many forms but few of these being adapted for use with screw spikes. In order to utilize this desirable form of fastening a special form of plate 20 must be provided. Such a plate must provide for a secure and extended bearing for the head of the screw spike, such bearing being preferably in the form of a plane surface whereby the flange or head of the spike 25 may be rotated freely thereon.

In many of the screw spike tie plates provision is made for direct contact between the rail and the head of the spike. This requires that the under surface of the spike 30 shall be spherical or at least curved to correspond to the angle of the top surface of the rail base. Thus only a line or point contact is secured between the spike and rail.

An object of my invention is to provide 35 means whereby an extended bearing surface is secured, and also to provide means for utilizing a screw spike having a flange with a horizontal plane under surface. These results are secured by the use of a clip such 40 as shown. However, due to inequalities and permissible variations, such a clip in order to certainly engage the rail base should have a limited line of contact with the tie plate, which contact line preferably acts as 45 a fulcrum. Thus a broad bearing is secured between clip, rail base and spike, and the clip is certain to engage the rail under all conditions of variation in material.

In my former application, Serial No. 50 827,947, filed March 29, 1914, issued as patent 1,100,848, dated June 23, 1914, I have set forth a form of tie plate which possesses in a degree the characteristics thus far set forth, and the present invention relates to 55 such further improvements in the art as conduce to even greater efficiency. Herein, I

provide for the interposition between the flanges of the tie plate and the edges of the rail base, of a portion of the clip which thus acts as a distance member bearing outwardly against the plate flange and inwardly against the rail, whereby the rail is securely fixed against lateral horizontal displacement and, the said interposed portion of the clip being preferably slightly tapered, 60 a wedging action is utilized to further clamp the rail within the plate. The clip furthermore rests with an outer wing portion on the flange of the plate and with an inner wing portion upon the upper face of the 65 rail base and, being forced downwardly by the screw spike, holds the rail against both lateral and vertical movement.

In order that the invention may be readily understood, I have in the accompanying 70 drawing and in the detailed description based thereon set forth a preferred embodiment of the invention. As, however, the particular embodiment is susceptible of modification without departing from the 75 spirit and essence of the invention it is to be understood that the drawing and description are to be taken in an illustrative and not in an unnecessarily limiting sense.

In the drawing—Figure 1 is a transverse 80 section of a railway rail with which an improved tie plate is associated; and Fig. 2 is a plan view of the same.

Having particular reference to the drawings, the reference numeral 11 designates a 85 cross tie upon which rests the tie plate which comprises a body portion 12, and upstanding lateral flanges 13, 13, the space between the flanges 13 being sufficiently greater than the width of the base 14 of the rail 15 to provide 90 a substantial side clearance between the edges of the rail and the said tie flanges. The tie plate is provided with spike apertures at points substantially half way between its flanges and the edges of the rail 95 100 with which it is designed to be associated.

Clips 16, 16 are employed for holding the rail in position relative to the plate, said clips each including a body portion 17 and laterally extending wing portions 18 and 19. 105 The body portion is adapted to fit snugly within the clearance space between the tie plate flange 13 and the edge of the rail and in order to provide for slight inaccuracies found in practice the said body portion 17 110 may advantageously be made with a slight downward taper so as to exert a lateral

wedging action as it is forced to its position by means of the screw spike 20 disposed within a central aperture of the clip and the aperture of the plate. The wing 18 of the 5 clip bears upon the tie plate flange 13 as a fulcrum and by means of the spike the wing 19 of the clip is clamped firmly upon the upper face of the rail base, the lower face of the wing 19 being preferably inclined to 10 fit the upper inclined face of the rail base. Thus it will be seen that the action of the screw spike upon the clip 16 acts to clamp the rail both horizontally and vertically in place within the rail clip which latter is 15 also by means of the spike securely affixed to the cross tie 11. It will be observed that there is here represented a combination of the tie plate and clip, the clip having shoulders abutting one against a shoulder of the 20 plate and the other directly against the rail base, while the upper face of the clip is plane to present a perfect bearing for the flat head of the screw spike.

I claim:

25 1. In a rail fastening device, the combination with a tie plate provided with opposite upstanding edge flanges, the inner edge faces of said flanges being perpendicular to the plane of the tie plate and the upper faces 30 of said flanges being disposed at right angles to said edge faces, of rail engaging clips having downwardly tapering body portions and oppositely-disposed laterally-extending wing portions engaging respectively the tie 35 plate flange and the rail base flange, the under face of said rail engaging wing portion being beveled to conform to the slope of the rail base flange and the tie plate flange en-

gaging wing portion having its under face conforming to the upper face of the tie plate 40 flange.

2. A combination tie plate and clip comprising a rail-supporting plate having a pair of oppositely facing flanges arranged to receive a rail base therebetween with side 45 clearance, and a clip having a wedge-shaped body portion with laterally projecting wings, the body arranged to snugly fit within the clearance space between the plate flange and rail base and the wings to overlie 50 the said rail base and plate flange respectively, the said plate and clip provided with means for holding the same in associated relation with a rail and with a suitable support, substantially as described.

55 3. A combination tie plate and clip comprising an apertured plate having a pair of oppositely facing flanges arranged to receive a rail base therebetween with side clearance, and an apertured clip having a wedge-shaped body portion with laterally projecting wings, the body adapted to snugly fit within the clearance space between the plate flange and rail base and the wings to overlie 60 the said rail base and plate flange respectively with the apertures of the plate and clip in alinement, the plate, rail, and clip adapted to be securely held in associated relation upon a tie by screw spikes disposed within 65 the apertures and bearing downwardly upon the upper face of the clip, substantially as described.

70 MORTIMER J. SILBERBERG.
